SHOE FITTER

Edward J. Bartkowski, 3015 S. 13th St., Milwaukee, Wis.

Filed July 5, 1963, Ser. No. 75,686

Term of patent 14 years

(Cl. D52—6)

FIG. 1

FIG. 2

FIG. 3

FIG. 4

I claim:

The ornamental design for a shoe fitter, substantially as shown.
